(57) **CLAIM**

The ornamental design for a bait station, as shown and described.

DESCRIPTION

In a preferred embodiment the nature of this product is as a device for attracting and killing crawling insects.

FIG. 1 is a left, top, frontal perspective view of a bait station embodying my new design;

FIG. 2 is a front elevational view thereof;

FIG. 3 is a rear elevational view thereof;

FIG. 4 is a left side elevational view thereof, the right side elevational view thereof being the mirror image thereof;

FIG. 5 is a top plan view thereof;

FIG. 6 is a bottom plan view thereof;

FIG. 7 is a left, top, frontal perspective view of a second embodiment that is identical to the first embodiment but for the upper cover being transparent and certain internal structures being visible as a result thereof;

FIG. 8 is a front elevational view thereof;

FIG. 9 is a rear elevational view thereof;

FIG. 10 is a left side elevational view thereof, the right side elevational view thereof being the mirror image thereof;

FIG. 11 is a top plan view thereof; and,

FIG. 12 is a bottom plan view thereof.

The broken line representation of bottom structure in FIG. 6 is for purposes of illustration only and forms no part of the claim.
